Primary Examiner — Paula Allen Greene

(74) Attorney, Agent, or Firm — QuickPatents; Kevin Prince

(57) **CLAIM**

The ornamental design for a casket collage frame, as shown and described.

DESCRIPTION

FIG. 1 is a front elevational view of a casket collage frame, showing our new design;

FIG. 2 is an enlarged perspective view thereof;

FIG. 3 is a front elevational view of FIG. 2;

FIG. 4 is a rear elevational view of FIG. 2;

FIG. 5 is a left-side elevational view of FIG. 2, the right-side elevational view being a mirror image thereof;

FIG. 6 is a top plan view of FIG. 2; and,

FIG. 7 is a bottom plan view of FIG. 2.

The broken lines in FIG. 1 depicting a casket show environmental matter that forms no part of the claimed design. The remaining broken lines in the figures figures depict portions of the casket collage frame that form no part of the claimed design.

1 Claim, 5 Drawing Sheets
